UNITED STATES PATENT OFFICE.

ALBERT L. SHEARS, OF SEATTLE, WASHINGTON.

INSULATOR.

No. 874,445.

Specification of Letters Patent.

Patented Dec. 24, 1907.

Application filed March 5, 1907. Serial No. 360,749.

To all whom it may concern:

Be it known that I, ALBERT L. SHEARS, citizen of the United States, residing at Seattle, in the county of King and State of Washington, have invented new and useful Improvements in Insulators, of which the following is a specification.

My invention relates to insulators for electric wires, and consists in the peculiar and advantageous construction hereinafter described and claimed.

In the accompanying drawings, forming part of this specification: Figure 1 is a side elevation of an insulator constituting one embodiment of my invention; a wire being shown as properly engaged with the insulator. Fig. 2 is a plan view of the same. Fig. 3 is a vertical, diametrical section. Fig. 4 is a view similar to Fig. 3, showing another mode of connecting the insulator to a support. Fig. 5 is a plan view of a modified insulator. Fig. 6 is a similar view of another modified insulator. Fig. 7 is a section taken in the plane indicated by the line 7—7 of Fig. 6 and showing the manner in which the modified insulator is connected with a yard-arm or other support.

Referring by letter to the said drawings, and more particularly to Figs. 1—3 thereof: A is a support which may be a yard-arm or any other device to which my novel insulator may be fastened, and B is the insulator. The said insulator is generally square in outline, and is provided with a vertical central bore a for the passage of a screw b which in some cases may be employed to connect it to the support A. At its bottom or lower end the insulator is provided with corner feet or bearings c and concavities d; the latter being arranged intermediate the feet and designed to render the lower portion of the insulator open so as to admit fresh air and permit water to drip away from the insulator. The said insulator is also provided with an upwardly-tapered upper portion e, lateral projections f in the under sides of which are grooves g, and slots h a pair of which is designed to be employed in combination with each projection f; the slots in said pair diverging from the projection as illustrated in Fig. 2. The outer walls of the slots h are beveled or tapered upward and inward, as indicated by i and best shown in Fig. 1, to facilitate placing of a wire in the slots, and this latter is also the function of the upper tapered portion e of the insulator.

In the practical use of the insulator it is designed to hold but two wires at one time; the plurality of slots h and projections f being provided in order that the insulator may not be rendered useless by the disablement of one slot or one projection. A wire is engaged with the insulator in the manner shown—that is to say, it is placed under one projection or knob f and in the groove g which holds it against outward displacement, and is brought up and placed in the slots h at opposite sides of said projection and is pressed down in said slots, whereby the insulator takes secure hold of the wire so that the same cannot move or be drawn endwise through the insulator. This as will be readily appreciated obviates the necessity of a lineman returning and taking up slack of the wire after he has fastened the wire to the insulator and also obviates the necessity of using extraneous means to fasten the wire to the insulator. It will be noticed, however, that while the wire is securely held to and against endwise movement through the insulator, the wire may be expeditiously and easily disengaged from the insulator by simply bending the wire out of one slot h, then from under the projection f and then out of the other slot h.

In the modification shown in Fig. 4, the insulator B' is provided with a threaded socket a' to receive a threaded pin b' on the yard-arm or other support A', but is otherwise similar to the insulator B shown in Figs. 1—3.

The modified insulator B² shown in Fig. 5 is preferably connected to the support A in the same manner as the insulator B, Figs. 1—3, but differs from said insulator B in that it has but two projections f', two pairs of slots h', and a differently shaped upwardly-tapered upper portion e'.

The modified insulator B³ of Figs. 6 and 7, has but one projection f² and two slots h², and its upwardly-tapered upper portion e² is shaped as shown. In connection with said insulator B³ is shown a mode of fastening the insulator, which like the other fastening means described may be employed in the connection of any of the insulators illustrated. The said mode of connection involves the provision of a dovetail groove C in the support A², and the provision of a lug D on the bottom of the insulator B², which lug may be secured in the groove by driving a nail E in the groove at the outer end of the lug. As

will be readily appreciated, the groove C may be quickly and easily cut in a yard-arm, and the lug on the insulator may be as readily placed and secured in said groove.

I have entered into a detailed description of the construction and relative arrangement of the parts embraced in the present embodiments of my invention in order to impart a definite understanding of the said embodiments. I do not desire, however, to be understood as confining myself to the said specific construction and relative arrangement of parts, as various changes in the form, construction and arrangement of parts may be made in practice without departure from the scope of my invention as defined in the claims appended.

Having described my invention, what I

claim and desire to secure by Letters-Patent, is:

An insulator having a lateral projection and wire-receiving slots diverging from the projection; the outer side of the projection and the outer sides of the outer walls of the slots being inclined upward and inward, and also having a portion tapered or inclined upward and inward from the upper side of the projection and the mouths of the wire-receiving slots.

In testimony whereof I, have hereunto set my hand in presence of two subscribing witnesses.

ALBERT L. SHEARS.
